UNITED STATES PATENT OFFICE.

ALFRED ORTHMANN, OF BARMEN, GERMANY, ASSIGNOR TO BARTHELS MANUFACTURING CO., OF GLENDALE, NEW YORK, A CORPORATION OF NEW YORK.

MACHINE FOR GUIDING BOBBINS IN RUNNING PATHS.

Application filed August 30, 1921. Serial No. 497,078.

To all whom it may concern:

Be it known that I, ALFRED ORTHMANN, residing at Barmen, Blankstr. 3, Germany, have invented certain new and useful Improvements in and Relating to Machines for Guiding Bobbins in Running Paths, of which the following is a specification.

This invention relates in general to braiding machines. The object of the invention is to provide a machine in which the entire means for guiding the bobbin carriers consists only of arcuate guiding surfaces. This is accomplished by arranging the sections of the raceway along which the bobbin carriers travel in different planes or along the peripheries of concentric circles. The bobbin carriers themselves are preferably with guide members which in addition to guiding the carriers along the part of the raceway with which they cooperate, also enable them to pass from one section of raceway to another in a satisfactory manner. In guiding the bobbin carriers from one section of raceway to another the said guide members are assisted by cams that revolve with the bobbin drivers and bear against the guide members when the bobbin carriers pass from one section of raceway to another. The said cams and guide members are also arcuate in shape. The invention is illustrated by way of example in the drawing in which—

Fig. 1 is a vertical section through a fragment of a braiding machine with raceways formed in vertical circular plates,

Fig. 2 a horizontal section on the line A—B of Fig. 1,

Fig. 3 a vertical section through a number of raceway sections or plates taken on the line C—D of Fig. 1, and

Fig. 4 is a similar section on the line E—F of Fig. 1.

In the drawing *a* is the lower part and *b* the upper part of a circular raceway. As shown in Fig. 1 these lower and upper parts lie in two different planes or, more correctly speaking in two different concentric circles, the part *b* being nearer to the center of the machine than the part *a* of the raceway. Attached to the bobbin carriers *c* are guide pieces or members *d*, *e* which cooperate or engage with the parts *a* and *b* respectively of the raceway. The guide members *d*, *e* of each bobbin carrier are connected to each other by a barrel *f* which has a collar *g*

adapted for engagement with grooves in 55 wheels, as *h*, so as to prevent the bobbin carriers from being flung outwardly by centrifugal force, and said guide members *d*, *e*, of each bobbin carrier are rigid with the carrier and convexed in opposite directions with their convex surfaces facing each other, as more particularly indicated in the several views, showing successive positions of the respective guide members, presented in Figs. 3 and 4, wherein the bobbin carriers *c* are denoted by the small dotted circles at the center of said guide members. The barrel *f* is of considerable thickness. The wheels *h*, journaled on shafts *i*, are integral with sleeves which carry cams *k*, *l* 60 and bobbin drivers *m*, *n*. The rotating drivers *m*, *n* carry the bobbin carriers around with them in the manner well known to all who are versed in the construction of braiding or plaiting machines. The functions 65 performed by the cams *k*, *l* are illustrated more clearly in Figs. 3 and 4. In each of these figures five raceway sections and corresponding positions of the cams and bobbin carriers in the same are shown. Fig. 70 3 shows a section through the inner and upper part of the circular raceway on the line C—D and illustrates alternating positions of the bobbin carriers. In Fig. 3, the parts "I", "II", "III", indicate the raceway part *b* for the guide members *e* and also said guide members, by solid lines, and denote the raceway part *a* and the guide members *d* cooperating therewith by dotted 75 lines. Fig. 3 thus represents a portion of 80 the circular raceway composed of the parts *b* and *a*, and the parts "I", "II", "III", may be said to be repetitions with the exception that they illustrate successive alternating 85 positions, on one quarter turns of the wheels 90 *h*, of the respective guide members *e*, *d* and cams *l* during the travel of the bobbin carriers along the said raceway. Fig. 4 shows a similar section on the line E—F of the 95 outer and lower part of the circular raceway 100 and illustrates alternating positions of the bobbin carriers which correspond to the bobbin positions shown in Fig. 3. In these figures the bobbin drivers which carry the 105 bobbin carriers around with them in the well known manner are not shown. The cams *k* and *l*, and the guide members *d* and *e* attached to the bobbin carriers are,

however, shown in section. In Fig. 4, the parts "I", "II", "III" indicate the raceway part *a* and the guide members *d* therefor by solid lines and the raceway part *b* and 5 guide members *e* therefor by dotted lines, and the parts "I", "II", "III" of Fig. 4 may be said to be repetitions except that they show successive alternating positions of the respective guide members *d*, *e* and 10 cams *k* on one-quarter turns of the wheels *h* during the travel of the bobbin carriers along the circular raceway composed of said parts *a*, *b*. Figs. 3 and 4 taken together illustrate by solid lines the movements of the 15 guide members *e*, *d* respectively and their respective cooperating cams *l*, *k* along the raceway parts *b*, *a*, and as further indicating the relation of the guide members *d* to the guide members *e*, and vice versa, Fig. 3 20 shows the guide members *d* by dotted lines, while Fig. 4 indicates the guide members *e* by dotted or broken lines.

In Fig. 3 the lower part *a* of the raceway is indicated in broken lines and represented 25 as if its arcs were of the same size as those of the upper part *b*. Since the parts shown in broken lines and those shown in solid lines in Figs. 3 and 4 are in different planes or concentric circles they will never be in 30 each other's way and can therefore never collide when traveling along the raceway. Thus in the case of division 1 of Fig. 3 for example, it should be remembered that the cams *l*, the guide member *e*, and the race- 35 way section *b* all lie in one and the same plane or circle, and this also applies to the guide members *e* and cams *l* of the other divisions 2, 3, 4 and 5 of Fig. 3. The arrows associated with the various divisions of Fig. 40 indicate the direction of rotation of the bobbin drivers. Let us consider the bobbin carrier located between the divisions 1 and 2 of Fig. 3 for example which is driven upwards in Fig. 3 by its driver. It is seen 45 that the upper end of the guide member *e* is engaged by the upper part *b* of the raceway. The cam or steadyng member *l* bears against the guide member *e* and keeps it steady during its further travel along the 50 raceway section of division 2, the steadyng effect being caused through the two parts *e* and *l* rolling against each other. As further explaining the movements of the bobbin carriers, I have lettered the bobbin carrier in the crossing between divisions 1, 55 2 of part I, Fig. 3, as *c'* and the carrier at the bottom of said division 2 as *c''*, and on the next one-quarter turn of the wheels *h* in the direction of the arrows in said 60 divisions 1, 2, the positions of the parts shown in divisions 1, 2 of part II will have been reached, the bobbin carrier *c'* having moved to the top of division 2 and fully engaging the raceway *b* through its guide member *e*, and the bobbin carrier *c''* having

reached the crossing between divisions 1 and 2 on its way to division 1. The guide member *d* of this carrier *c''* previously engaging the part *a* of the raceway is now gradually disengaging from said part *a* and the 70 guide member *e* of the same bobbin carrier *c''* is cooperating in the crossing with the raceway part *b* in division 1, part II, the cam *l* in division 2, part II, steadyng the said guide-member *e* during its further 75 travel into raceway part *b*. Another quarter turn of the wheels *h* will create the bobbin carrier positions shown in part III of Fig. 3.

In Fig. 4 the movements of said bobbin carriers *c'*, *c''*, and guide members *d* with relation to the raceway part *a*, are shown. As has already been pointed out the driving of the bobbin carriers is accomplished by means of bobbin drivers (not shown in Figs. 80 3 and 4). The bobbin carrier shown between the raceway sections of divisions 2 and 3 in Fig. 3 passes over to the section or division 3 because the lower end of its 85 guide member *d*, Fig. 4, is engaged by the part of the raceway *a* situated in the same plane or circle with this member *d*, while the associated guide member *e* passes by the raceway *a* without touching it. A steadyng member or cam *k* not shown in Fig. 3, 90 but in evidence in Fig. 4, steadyng the part *d* of the bobbin carrier during its further travel onto the raceway section of division 3. It is thus seen that the bobbin carriers 95 are well guided and steadyng at the places where they pass from one raceway section to another, or from one part *a* to another 100 *b* of the raceway or vice versa.

The parts *a* and *b* of the raceway as shown may be said to be situated in different 105 planes, concentric circles or tiers and their location is described by corresponding terms in the following claims.

In Figs. 1 and 2, I number the bobbins 110 and direct attention to the fact that they are beyond or exterior to the guide plates and that the thread from each bobbin, following the arrow lines shown, passes through a hole in the arm 11 and thence enters the adjacent or lower back end of the bobbin carrier *c* and passes through a channel extending longitudinally through said carrier and issues at the forward end of the carrier. The series of radial dotted lines at the right hand portion of Fig. 2 indicate 115 the paths of the braiding threads converging at the center of the machine.

There are gaps or spaces in the crossings between the concave arcs of the raceway parts *a*, *b*, and the guide members *d*, *e*, 125 should be a little longer than these gaps or spaces. In Fig. 4, part "I" I denote the length of the gap between one pair of concave arcs by the dotted lines *Z'* and the length of a guide member *d* at said gap 130

by the dotted line Z, so as to indicate the difference in length between the gaps and guide members.

The drawings illustrate my invention embodied in a horizontal braiding machine but is equally applicable for vertical braiding machines.

I claim:

1. In a braiding machine, guide plates, 10 bobbin carriers, a raceway for guiding the bobbin carriers formed in the margins of said plates and consisting only of concave arcs of circles, and driving elements for driving the carriers arranged at opposite 15 sides of the said guide plates.

2. In a braiding machine, guide plates, bobbin carriers, a raceway for guiding the bobbin carriers formed in the margins of said plates and consisting only of concave 20 arcs of circles arranged in different tiers, guiding members with convex guiding surfaces on the bobbin carriers also arranged in different tiers, and carrier driving elements arranged at opposite sides of the said 25 guide plates.

3. In a braiding machine, guide plates, bobbin carriers, a raceway for guiding the bobbin carriers formed in the margins of said plates and consisting only of concave 30 arcs of circles arranged in different tiers, guiding members with convex guiding surfaces on the bobbin carriers also arranged in different tiers, and members adapted to rotate with the drivers and having convex 35 circular surfaces adapted to engage with the convex surfaces of the said guiding members.

4. In a braiding machine, guide plates, bobbin carriers, a raceway for guiding the 40 bobbin carriers formed in the margins of said plates and consisting only of concave arcs of circles arranged in different tiers so as to form gaps between the guide plates of different tiers, guiding members with 45 convex guiding surfaces on the bobbin carriers also arranged in different tiers, the lengths of the guiding members exceeding the lengths of the said gaps, and driving elements for driving the carriers arranged 50 at opposite sides of the said guide plates.

5. In a braiding machine, cylindrical annular guide plates, bobbin carriers, and a raceway for guiding the bobbin carriers formed in the margins of said annular guide 55 plates.

6. In a braiding machine, annular guide plates, bobbin carriers, a raceway for guiding the bobbin carriers formed in the mar-

gins of said annular guide plates and bobbins on the bobbin carriers disposed at the 60 exterior of the annular guide plates.

7. In a braiding machine, annular guide plates, bobbin carriers provided with thread guiding channels, bobbins on the bobbin-carriers disposed at the exterior of the annular 65 guide plate, and a raceway for guiding the bobbin carriers formed in the margins of said annular guide plates, the said channels being situated in the guiding portions of the said bobbin carriers. 70

8. In a braiding machine, cylindrical annular guide plates, bobbin carriers, a raceway for guiding the bobbin carriers formed in the margins of said annular guide plates and means for preventing longitudinal 75 placement of the bobbin carriers.

9. In a braiding machine, guide plates, bobbin carriers, a raceway for guiding the bobbin carriers, formed in the margins of said plates, driving elements for driving 80 the carriers, and members having convex circular surfaces, rotating with the drivers and adapted to support the carriers in passing from one driver to another.

10. In a braiding machine, guide plates, 85 bobbins carriers, a raceway for guiding the bobbin carriers, formed in the margins of said plates and consisting only of concave arcs of circles arranged in different tiers, guiding members with convex guiding surfaces 90 on the bobbin carriers also arranged in different tiers, and staggered cams also arranged in different tiers adapted to rotate with the drivers and having convex circular 95 surfaces adapted to engage with the convex surfaces on the said guiding members.

11. In a braiding machine, guiding plates, bobbin carriers, a raceway for guiding the carriers formed in the margins of said plates and consisting only of concave arcs of circles arranged in different tiers, guiding members with convex guiding surfaces on the bobbin carriers also arranged in different tiers and driving elements for driving 100 the carriers, the distance of the axes of two adjacent driving elements being greater than the sum of the radii of the concave arcs of circles of the raceway at these driving elements minus the diameter of the carrier 105 spindle. 110

In testimony whereof I have affixed my signature in presence of two witnesses.

ALFRED ORTHMANN.

Witnesses:
